UNITED STATES PATENT OFFICE.

HENRY RHOECKER, OF COLUMBUS, OHIO.

CAR DOOR.

Application filed July 15, 1921. Serial No. 484,894.

To all whom it may concern:

Be it known that I, HENRY RHOECKER, a citizen of the United States of America, residing at Columbus, in the county of Franklin and State of Ohio, have invented new and useful Improvements in Car Doors, of which the following is a specification.

The object of the invention is to provide a simple, efficient and durable freight car door which is protected against attack from the outside by levers or tools designed to force the same from its mountings to give surreptitious access to the car, which is adapted to prevent the escape of goods even of the granular form from the interior of the car, which is adapted to be locked against entrance at one side from the interior of the car so that but one sealing or sealed lock is required, and to provide a door mounting whereby the opening and closing movement thereof when released is facilitated and whereby damage to the door by contact with exterior objects adjacent to the car is eliminated to insure full closure of the structure; and with these objects in view the invention consists in a construction and combination of parts of which a preferred embodiment is shown in the accompanying drawings, wherein:—

Figure 1 is a side view of a car having a door construction embodying the invention.

Figure 2 is a horizontal section of the same showing one of the doors interiorly and the other exteriorly locked.

Figure 3 is a vertical section on the plane indicated by the line 3—3 of Figure 2.

Figure 4 is a detail view of the interior lock.

Figure 5 is a vertical sectional view of the interior lock.

Figure 6 is a detail view of the interior lock bolt.

Figure 7 is a similar view of the exterior lock shackle.

The door 10 is mounted for horizontal sliding movement between the car wall 11 and a guide 12 whereby it is housed and protected when in an open position, the lower edge of the door extending through a slot 13 in the floor 14 of the car and resting upon bearing rollers 15 extended transversely between and mounted in angle bars 16 and 17 which marginally protect the guide slot and sustain the wear incident to the sliding movement of the door. The upper edge of the door is mounted in a suitable channeled

guide 18 also preferably of metal which is extended to form a protection 19 for the upper wall of the door opening just as the horizontal flange 16^a of the angle bar 16 constitutes a sill plate to protect the lower wall of the door opening.

The door is adapted in its closed position to be received by a keeper 20 arranged vertically at the inside of the vertical wall of the door opening adjacent to the free edge of the door, and the latter overlaps the jamb or wall of the door opening as indicated in Figure 2. The door carries a stop flange 21 for abutting engagement with the wall or jamb of the door opening at the free edge of the door when the door is in the closed position and in this stop flange is provided an opening for the reception of a staple 23 with which is engaged the looped shackle 24 held to the frame of the door by means of retaining chain 25 and provided with the usual slots 26 in the arms thereof for the reception of the sealing strip or band 27.

Where the car as in the construction illustrated is provided with a door at each side, each door is preferably provided with an exterior fastening means such as above described including the stop flange, staple and shackle, and in addition thereto each door is provided with an interior fastening device indicated at 28 and consisting of a bolt 29 extending through a seating block 30 on the frame of the car to span the guide in which the door operates in the path of the adjacent or rear edge of the door to obstruct and prevent the movement thereof, the terminal of said bolt being engaged with a socket 30' in the wall of the car. This bolt is held in place against loss or removal by a suitable retaining chain 33 and is adapted to be secured in its door engaging position by a locking pin 32 also having a retaining chain 31.

Thus when it is desired to load the car it is preferable to secure one of the doors at the inside so as to avoid the necessity of sealing both doors exteriorly; and after the car has been loaded the other door may be locked by means of the exterior means above described, and sealed to afford means of detection in the event that the door should be surreptitiously opened.

The arrangement of the doors at the inner surfaces of the walls of the car protects them from contact with adjacent objects and from being opened by prying them loose from

their hangings or mountings as in the ordinary practice, the portions of the guides 12 adjacent to the door openings being fortified by stout uprights 34 to prevent displacement of the rear edges of the doors while the stop flanges 21 serve to protect the free or front edges of the doors.

Having described the invention, what is claimed as new and useful is:—

- 10 1. A car door mounted for horizontal sliding movement at the inner surface of the car wall and having upper and lower guides for the corresponding edges thereof and a housing guide extending from the rear edge 15 thereof and parallel with the side wall of the car for the reception of the door when open, the door being adapted at its free or front edge to overlap the inner surface of the door jamb or frame in its closed position, a guide 20 clip disposed to receive the overlapping portion of said edge, and an outwardly extending stop flange being provided adjacent to the free or front edge of the door and extending the full height thereof for abutting 25 contact with the inner surface of the door jamb or frame.

2. A car door mounted for horizontal sliding movement at the inner surface of the car wall and having upper and lower 30 guides for the corresponding edges thereof and a housing guide extending from the

rear edge thereof and parallel with the side wall of the car for the reception of the door when open, an interior locking means being provided for the rear edge of the door and 35 consisting of a bolt for spanning said housing guide in the path of the door, and means for securing said bolt in its operative position.

3. A car door mounted for horizontal 40 sliding movement at the inner surface of the car wall and having upper and lower guides for the corresponding edges thereof and a housing guide extending from the rear edge of the door and parallel with the side 45 wall of the car for the reception of the door when open, and an interior locking means provided at the rear edge of the door and consisting of a seating block mounted on the inner face of the housing guide, a bolt passing transversely through the seating block and adapted to span the space between the housing guide and the car wall adjacent the rear edge of the door when closed, and a 50 pin removably engaged with an axial bore 55 in the seating block and passing transversely through a registering hole in the bolt when the latter is in spanning relation with the door edge.

In testimony whereof he affixes his signature.

HENRY RHOBECKER.
